UNITED STATES PATENT OFFICE.

MARK THOMAS DENNE, OF RUSHDEN, ENGLAND.

SEWING-MACHINE.

1,264,284.

Specification of Letters Patent. Patented Apr. 30, 1918.

Application filed May 18, 1914. Serial No. 839,209.

To all whom it may concern:

Be it known that I, MARK THOMAS DENNE, a subject of the King of Great Britain and Ireland, residing at Rushden, Northamptonshire, England, have invented new and useful Improvements in and Relating to Sewing-Machines, of which the following is a specification.

This invention has reference to improvements in sewing machines in which the tension on the thread is automatically relieved when the machine stops and restored when the machine is again started.

The known tension-release devices have the serious defect that if the machine be started or stopped gradually, the tension is applied or released gradually, with the result that the first or last few stitches are not properly drawn in, and the object of my invention is to insure that the thread tension device shall be put into action before the machine has been started and only released after the machine has been stopped.

With this object in view, my invention comprises, in a power-driven sewing machine which is started and stopped by moving a control member, the combination with the thread tension device of a tension-releasing member which is actuated and controlled by the said control member in such a manner that the first portion of the movement of said control member in a direction to start the machine, but before the machine is started, causes said tension-releasing member to permit the tensioning of the thread, which tensioning is maintained during the whole time that the machine is in operation, and can only be released after the machine has completely stopped.

In carrying my invention into practice, I provide a rod or the like, one end of which is attached to the usual starting treadle, which rod not only controls the movements of the driving clutch, but also controls the movements of the tension device through the tension-releasing member in such a manner that the first portion of the movement of the treadle will put the thread-tensioning device into operation to grip the thread frictionally but without putting the driving clutch into operation, the latter being effected only by the subsequent further movement of the treadle, and, conversely, the first portion of the treadle movement as it is being released will effect the uncoupling or disengagement of the driving clutch but without putting the

thread-tensioning device out of action, the latter being rendered inoperative only by the further and complete release of the treadle after the machine has already stopped. 60

I have illustrated my invention in the accompanying drawings in which Figures 1 and 2 show side and end elevations, respectively, of one form of tension device and tension-releasing means, together with means 65 for controlling the same in accordance with the invention, and Fig. 3 illustrates the application of the invention to one form of power driven sewing machine fitted with such a tension device and tension releasing 70 means, such power driven machine being a conventional form and forming no part of the present invention. In carrying my invention into practice I employ the ordinary control treadle V, the depression of which 75 effects the coupling together of the ordinary friction clutch members T, U usually employed to drive the machine but with this difference that the connection between the treadle and the usual wedge W or equivalent 80 whereby the friction members are made to engage is such that the treadle may be depressed for some distance—against the action of the usual spring A—before the wedge is made to move. 85

This lost motion (so far as the starting of the machine is concerned) of the treadle is made use of by me to put the thread tensioning device into operation for which purpose I may employ the following means and 90 connections. The thread tensioning device may be the well known tension disks B, C and which I support between two friction disks D, E, one of which latter E is carried by a bracket F on the machine frame and 95 the other D of which is provided with a spindle G passing centrally through the tension disks and the other friction disk and extending some distance beyond the latter. Surrounding a portion of the extending part 100 of the spindle G I provide a spring H one end of which acts against the bracket F referred to and the other against an adjustable nut J on the spindle G whereby the tension of the spring H may be adjusted, the spring 105 normally serving to draw the friction disks D, E, together to thereby frictionally grip the tension disks B, C, between them.

K is a vertical rod which is suitably connected to the usual treadle V by which the 110 machine is started. This rod is provided with the adjustable spring A which nor-

10 mally serves to raise the rod and the treadle to their highest positions and between the top end of the said rod K and the rear end of the disk carrying spindle G I provide a bell crank lever L arranged in such a manner that when the rod is in its highest position it will have raised one arm m of the bell crank lever and thereby caused the other arm n of said lever to press back the spindle—
15 5 overcoming in doing so the tension of the spring H thereon—and with the latter the friction disk D carried thereby thus freeing the tension disks.

When the operator depresses the treadle 15 the treadle rod K will be pulled down thereby freeing the bell crank lever L and permitting the spring H referred to to bring about the frictional engagement of the tension disks B, C with the friction disks 20 D, E.

In order to prevent the bell crank lever L rotating too far when the treadle rod K is pulled down I may interpose a light spring O to support the bell crank lever 25 in about its normal position and I may provide one arm (or may be both arms) of the bell crank lever with a set screw P to permit fine adjustment thereof relatively to the treadle rod and to the friction disk 30 spindle. The treadle rod K has a dog Q secured upon it which in the stopping position (as shown in Fig. 3) is slightly separated from the end of a lever R that is connected at its other end to the usual clutch 35 operating wedge W. When the operator depresses the treadle V the initial downward movement of the rod K will release the spring H so that the latter will apply the tension, as above described. During this 40 initial movement the lost motion between the dog Q and the lever R is taken up so that when the tension has been applied, then during the further downward movement of the rod K, the dog Q will act on the lever R 45 and thereby operate the latter to cause the clutch-operating wedge W to force the thrust block S into contact with the driving member T of the clutch and to move the same along the driving shaft into contact 50 with the clutch member U thereby to start the machine. When the rod K is moved in the reverse direction the initial movement thereof will result in permitting the clutch to be unclutched, this unclutching 55 operation being completed before the rod K completes its upward movement, and during the final upward movement of the rod K, the latter acts on the tension-releasing member L thereby to cause it to release the 60 tension. The tension is thus applied before

the machine is started, but is not released until after the machine has been brought to rest.

I wish it however to be understood that I do not limit the scope of my invention 65 to the particular mechanism described for controlling the tension device nor to the particular device described.

In addition to the usual driving means—for example a friction clutch—I may provide any known means whereby so soon as the friction clutch is thrown out of action, the machine is brought substantially instantly to a stop.

What I claim as my invention and desire 75 to secure by Letters Patent is:—

1. In a power driven sewing machine, the combination with a control member, of a reciprocable clutch-operating element operated by the control member, a thread tension device, and a tension-releasing member which is interposed between said control member and the tension device so that reciprocating movement of the control member will operate to release and apply the ten- 80 sion, said control member being adapted to release the tension only after the machine has been stopped and to permit the tension to be automatically applied before the machine can be restarted. 90

2. In a power driven sewing machine, the combination with a clutch for actuating said machine, of a control member, a reciprocable clutch-operating element connected to the control member to be actuated thereby, 95 a thread tension device, means for automatically applying the tension, means interposed between the clutch-operating element and the clutch by which the clutch is applied during the final movement of said element in one direction and is released during the initial movement of said element in the opposite direction, and means interposed between said element and the tension device whereby the tension will be 100 applied during the initial movement of said element in the first-named direction and will be released during the final movement of said element in the opposite direction whereby the tension will only be released 105 after the clutch has been disconnected and will always be applied before the clutch is thrown into operation. 110

In testimony whereof I have signed my name to this specification in the presence 115 of two subscribing witnesses.

MARK THOMAS DENNE.
